Attorney.

UNITED STATES PATENT OFFICE.

WILLIAM GOTTLIEB, OF PORT JERVIS, NEW YORK.

METALLIC TIE.

1,192,300.

Specification of Letters Patent. Patented July 25, 1916.

Application filed April 14, 1916. Serial No. 91,167.

To all whom it may concern:

Be it known that I, WILLIAM GOTTLIEB, a citizen of the United States, residing at Port Jervis, in the county of Orange and State of New York, have invented new and useful Improvements in Metallic Ties, of which the following is a specification.

The present invention relates to an improvement in the construction of metallic ties and means associated therewith for retaining the rails thereon.

An object of the invention is to produce a tie comprising two similar sections provided with means for associating the same in an adjusted position, and each of the sections having associated therewith a rail sustaining member which is adapted to afford a desired amount of resiliency to the said rails.

20 A further object of the invention is to produce a metal tie having means thereon for securing the rails thereto which shall embody the desirable features of simplicity in construction, cheapness in manufacture 25 combined with strength and efficiency.

With the above and other objects in view the improvement resides in the construction, combination and arrangement of parts set forth in the following specification and 30 falling within the scope of the appended claims.

In the drawing: Figure 1 is a top plan view of the improvement illustrating rails secured thereon and one of the members of 35 the tie being broken away and having parts shown in section, Fig. 2 is an enlarged sectional view approximately on the line 2—2 of Fig. 1, Fig. 3 is a sectional view approximately on the line 3—3 of Fig. 1, Fig. 4 is a 40 sectional view approximately on the line 4—4 of Fig. 1, and Fig. 5 is a perspective view of one of the rail seats. Fig. 6 is a perspective view of a modified form of tie.

As shown in the drawing I produce a 45 metallic tie comprising two members both of a similar construction and whereby each of said members may be formed in a single mold or may be struck by a single die. Each of the sections 6—6 comprises a hollow 50 member that has its outer portion substantially square or rectangular in cross section and which is cut from its inner end through its top and bottom plates approximately central and the edges provided by the said cuts 55 formed with teeth 7 adapted to interlock when the sections are assembled. The re-

duced portions provided by the said cuts have their ends arranged angularly, as indicated by the numerals 8, and the said sections at the inner end of the said reduced 60 portions are also cut angularly, as indicated by the numerals 9, and the angular ends 8 may abut with the angular shoulders 9 when the tie sections are associated. The vertically straight side walls of each of the sections, at the reduced portions thereof, are provided with openings through which pass securing elements in the nature of bolts 10 having retaining nuts 11, and the side of one or both of the sections may be provided with 70 a plurality of bolt openings 12 whereby the said bolts 10 may pass therethrough to secure the sections in a longitudinally adjusted relation with each other.

The tie upon its upper face and adjacent 75 its ends is formed with centrally disposed round openings 13 through which extend the centrally arranged sleeves 14 provided upon the rail seats 15. The upper plates of the rail seats are flat and these plates are of a 80 length approximately equaling the width of the tie, and each of the said plates upon one of its longitudinal edges and adjacent its corners is formed with inwardly extending rail engaging tongues 16, while the said 85 plates, opposite the tongues are provided with openings 17 through which are passed the shanks of bolts 18 that engage with clips 19 that contact with the base flange of the rail opposite that engaged by the hooks 90 16. In order to facilitate the engagement of the bolts 18 with the clips 19 I provide the ties inward of the openings 13, and adjacent one of the sides of the said tie, with an elongated opening 20 and I also provide 95 the said upper face of the tie directly below the bolt openings 17 with slots 21. The opening 20 is of a sufficient size to permit of the insertion of the hand of an operator therethrough to the interior of the tie so 100 that the said operator may insert the bolts 18 through the slots 21 to direct their threaded shanks through the openings 17 in the rail seats 15 and permit of the same threadedly engaging with the clips 19. 105

Received within the sleeves or sockets 14 of the rail seats 15 are helical springs 23 which exert a tension between the top plate of the said seats and the lower plate or wall of the hollow tie and which normally force 110 the rail seats outwardly with relation to the tie. To insure a perfect movement of the

rail seats in a vertical direction, as well as to limit the outward movement thereof by the influence of the springs 23, I secure to the tie, central of the said rail seats, guide members 24 which are substantially Z-shaped in side elevation and have their lower flanges 25 connected with the tie, and vertical plates 26 contacting with the opposite longitudinal edges of the top plate of the rail seats and their upper ends inturned, as at 27, to overlie the base flanges of the rails 22. The flange or inturned portions 27, of the outer members 24, are disposed between the hooks 16, of the rail seats, while the inner members are disposed between the clips 19, as clearly shown in Fig. 1, of the drawing. The adjustment of the tie sections is desirable as the arrangement permits of the securing of the rails thereon for either a wide or narrow gage track.

In Fig. 6, of the drawing, a modified form of tie has been shown. The construction of the tie shown is identical with that of the preferred form shown in Fig. 1, except that the sections 6—6, of the tie, instead of having the longitudinally straight toothed edges and the angular ends on the reduced portions, they are cut on a bias from points intermediate the ends of the tie to produce a tapering end portion for each section 6—6. Teeth 7', are formed on the edges of the top and bottom walls of the tie sections at the bias for interlocking engagement to hold the sections of the tie in various adjusted positions as will be understood.

From the above description, taken in connection with the accompanying drawing, the simplicity of the device, as well as the advantages thereof will, it is thought, be perfectly apparent to those skilled in the

art to which such invention appertains without further detailed description.

Having thus described the invention, what I claim is:

1. The combination with a hollow metal tie, of rail seats upon the tie, spring members between the rail seats and the ties, each of said rail seats having one of its ends formed with rail engaging hooks, rail-engaging clips connected with the other end of the rail seats, and guide members secured to the tie contacting with the rail seats between the rail engaging elements thereof and having inturned portions which overlie the base flanges of the rail.

2. The combination with a hollow metal tie, of rail seats comprising flat plates having socket members which extend through openings in the tie, a helical spring in each of the sockets and exerting a pressure between the rail seat and the lower wall of the tie, the rail supporting plate of each of the seats having one of its edges provided with rail engaging hooks, removable rail engaging clips secured to the opposite edge of each of said seats, guide members for the rail seats disposed to the opposite sides of the said seats and connected to the ties and contacting with the seats between the rail engaging elements thereof, said guide members having their upper edges flanged inwardly to overlie the rail seats and to normally contact with the upper face of the base flange of the rails.

In testimony whereof I affix my signature in presence of two witnesses.

WILLIAM GOTTLIEB.

Witnesses:
